HENRY J. MASTENBROOK, OF CLEVELAND HEIGHTS, OHIO, ASSIGNOR TO THE SWART-WOUT COMPANY, OF CLEVELAND, OHIO, A CORPORATION OF OHIO

STEAM DESUPERHEATER

Application filed March 29, 1929, Serial No. 351,005.

This invention relates to improvements in steam desuperheaters, in which the temperature of superheated steam may be reduced for use in apparatus where saturated steam, or 5 steam of a temperature lower than that in the line, is needed.

The object of my invention is to provide a device through which superheated steam may be passed and in which its temperature 10 may be reduced by intercommingling, and intimate contact, with water, the latter being atomized and vaporized by the velocity and temperature of the steam.

A further object is to provide a steam de- 15 superheater which is simple in construction and efficient in operation.

In the drawings Fig. 1 is a vertical sec- 20 tional view of one form of steam desuperheater constructed according to my invention; Fig. 2 is a sectional detail view of the water spray nozzle; and Fig. 3 is a view cor- 25 responding to that of Fig. 1 of a modified form.

In the form illustrated in Fig. 1 of the ac- 30 companying drawings the desuperheater comprises a hollow bowl-like casting 10 pro- 35 vided at its top with an outlet 11. Below the outlet 11 and formed as an integral part of the bowl 10 is an annular downwardly 40 projecting lip 12 the purpose of which will appear as the description proceeds. The bowl 45 is also provided with an inlet 13 for super- heated steam which enters at the top of the bowl and includes a portion 14 which ex- 50 tends downwardly in the bowl and is concen- tric therewith. The discharge end 15 of the inlet is constricted and is disposed below the 55 annular lip 12. A water inlet pipe 16 ex- tends through the top of the casting 10 and 60 into the steam inlet conduit 14 terminating at a point concentric with the downwardly ex- 65 tending portion 14 and a short distance above the constricted end portion 15. Screwed into the end of the pipe 16 is a conical water de- 70 flecting member 17 which disperses the water 75 in a fine spray within the steam inlet 14.

The bottom of the bowl 10 is closed by a 80 cap 18 which is provided at its center with an aperture 19 into which a drain pipe 20 85 is secured. The drain pipe 20 may be con- 90

nected to any suitable steam trap. Screwed into the inner end of the opening 19 is a pipe 21 which extends upwardly a short distance in the casing 10. On the upper end of the pipe 21 is a T 22.

In operation the superheated steam enters 55 through the inlet 13 and passes through the restricted opening 15 into the bowl 10 from where it escapes through the outlet 11 in the top of the bowl. To reduce the temperature 60 of the superheated steam, water is introduced through the pipe 16 in the form of a fine spray so an intimate mixing of the water with the column of steam is effected. A large por- 65

tion of the water is thus vaporized and in 70 the vaporization of this water the tempera- 75 ture of the steam is materially decreased. The water which is not vaporized fills the lower end of the bowl until it reaches the level of the T 22. Due to the rush of the 80 steam from the discharge 15 into the bowl, the water in the bottom of the bowl will assume the position illustrated in dot and dash lines in Fig. 1. A large amount of this water 85 will be vaporized by the contact of the steam therewith, and any excess will pass out through the overflow 21. The annular lip 90 95 12 prevents the steam from forcing water which has not been vaporized into the outlet 11. It is of course apparent that the amount of water admitted through pipe 16 is controlled usually thermostatically so that the superheated steam may be reduced to any desired temperature and maintained at such temperature irrespective of the fluctuations 100 in the superheated steam line.

In the form of desuperheater illustrated in Fig. 3, the hollow bowl like casting is made in two parts. The top part 25 is provided with an outlet 26 and an inlet which includes 95 a portion 27 concentric with the casting 25. The lower part 28 is merely a hollow cup shaped member which is provided in its bottom with a threaded opening 29 into which the drain pipe 20 and overflow pipe 21 are 100 secured, the overflow pipe 21 being provided at its top end with the T 22, the same as in the form above described. The parts 25 and 28 are provided at their adjoining ends with flanges 30 and 31 respectively which are 105

5 apertured to receive bolts 32 for securing the parts together. Interposed between the parts 25 and 28 is a metal ring member 33, the inner edge of which extends into the bowl and is bent downwardly to form an annular lip 34, corresponding to the lip 12 in the form illustrated in Fig. 1.

10 The lower end of the steam inlet conduit 27 terminates in the same plane as the bottom end of the member 25, and is provided with a flange 35 apertured to receive bolts 36. Bolted to the flange 35 is a flanged extension 37 and between the two as they are bolted together is secured a plate 38 provided 15 at its center with an aperture 39 materially less in diameter than the conduit 27, which serves the same purpose as the constricted portion 15 in the form first described, namely, to increase the velocity of the steam as 20 it leaves the conduit 27. Extending into the inlet 27 and terminating a short distance above the plate 38 is the water inlet pipe 16 provided with the nozzle 17.

25 The operation of this desuperheater is of course the same as the one above described, the lip portion 34 serving to prevent the water in the bottom of the bowl 28 from being carried over into the outlet 26. The force of the steam as it escapes through the opening 39 in the plate 38 causes the water in the bottom of the bowl 28 to assume a position approximating that shown in dot and dash lines and at the same time evaporating considerable of it, the exposed surface of the 35 water being greatly increased due to the action of the steam thereon.

30 It is of course understood that the water in the water inlet 16 must be under a pressure greater than the pressure of the steam in the steam line.

40 Having thus described my invention, what I claim is:

45 1. A steam desuperheater comprising a vertically disposed substantially annular casing composed of an upper part provided with an outlet, an inlet conduit including a portion extending downwardly into and arranged in concentric relation with the upper part of said casing, the bottom ends of said upper part and of said inlet conduit terminating in the same plane, a member secured to the bottom end of said inlet provided with an opening materially less in diameter than the said inlet for increasing the velocity of the fluid as it is discharged from said inlet conduit, a water inlet pipe projecting into said inlet conduit terminating at a point concentric with and slightly above the bottom end of the inlet, and means at the end of the pipe for deflecting the water in the form of a fine spray, an elongated bowl portion secured to the bottom end of the upper member for closing the same, means in the bottom of said bowl for draining excess water therefrom, a ring member secured between the upper part and said bowl, the inner diameter of said ring being less than the diameter of said casing whereby an annular flange is provided on the inner periphery of said casing below the outlet to prevent water from being forced upwardly along the wall of the casing by the force of the steam.

50 2. A steam desuperheater comprising a vertically disposed substantially annular casing composed of an upper part provided with an outlet, an inlet conduit including a portion extending downwardly into and arranged in concentric relation with the upper part of said casing, the bottom ends of said upper part and of said inlet conduit terminating in the same plane, a member secured to the bottom end of said inlet provided with an opening materially less in diameter than the said inlet for increasing the velocity of the fluid as it is discharged from said inlet conduit, a water inlet pipe projecting into said inlet conduit terminating at a point concentric with and slightly above the bottom end of the inlet, and means at the end of the pipe for deflecting the water in the form of a fine spray, an elongated bowl portion secured to the bottom end of the upper member for closing the same, a drain pipe extending upwardly in the bottom of said bowl through which accumulated water may flow after a predetermined level is reached.

55 3. A steam desuperheater comprising a vertically disposed substantially annular casing composed of an upper part provided with an outlet, an inlet conduit including a portion extending downwardly into and arranged in concentric relation with the upper part of said casing, the bottom ends of said upper part and of said inlet conduit terminating in the same plane, a member secured to the bottom end of said inlet provided with an opening materially less in diameter than the said inlet for increasing the velocity of the fluid as it is discharged from said inlet conduit, a water inlet pipe projecting into said inlet conduit terminating at a point concentric with and slightly above the bottom end of the inlet, and means at the end of the pipe for deflecting the water in the form of a fine spray, an elongated bowl portion secured to the bottom end of the upper member for closing the same, means in the bottom of said bowl for draining excess water therefrom, a ring member secured between the upper part and said bowl, the inner diameter of said ring being less than the diameter of said casing whereby an annular flange is provided on the inner periphery of said casing below the outlet to prevent water from being forced upwardly along the wall of the casing by the force of the steam.

60 4. A steam desuperheater comprising a vertically arranged casing having its opposite ends closed, a conduit for steam projecting into said casing adjacent the upper end thereof and arranged to discharge steam axially of said casing toward the bottom thereof, the said conduit being provided with a construction adjacent its delivery end through which the steam must pass, there being an annular passage provided between

the axially extending portion of the conduit and the casing and the said casing having an outlet for steam adjacent the upper end thereof, means for delivering water in a fine spray in the said conduit adjacent to the constricted portion thereof, and a drain pipe connected with the bottom of the casing and extending upwardly therefrom to a point substantially below the lower end of said conduit and with its inlet opposed to the delivery end thereof.

5 5. A steam desuperheater comprising a vertically arranged casing having a closed top and bottom and having a conduit extending thereinto from one side thereof adjacent to the top and projecting axially downwardly within the casing and spaced therefrom, the said casing also having an outlet for steam in the upper portion thereof, said conduit 10 having a constriction adjacent the lower end thereof through which steam must pass, and a water conduit extending into the first mentioned conduit above and adjacent to the constricted portion thereof for supplying water 15 in a spray into the first mentioned conduit, the said casing having an annular downwardly projecting lip surrounding the downwardly extending portion of the first mentioned conduit and spaced therefrom.

20 6. A steam desuperheater comprising a vertically arranged casing having a closed top and bottom and having a conduit extending thereinto from one side thereof adjacent to the top and projecting axially 25 downwardly within the casing and spaced therefrom, the said casing also having an outlet for steam in the upper portion thereof, the said conduit having a constriction adjacent the lower end thereof through which steam must pass, a water conduit extending 30 into the first mentioned conduit above and adjacent to the constricted portion thereof for supplying water in a spray into the first mentioned conduit, the said casing having an 35 annular downwardly projecting lip surrounding the downwardly extending portion of the first mentioned conduit and spaced therefrom, and a drain pipe extending upwardly from the bottom of the casing with 40 to its inlet opposed to and spaced from the delivery end of the first mentioned conduit.

In testimony whereof, I hereunto affix my signature.

HENRY J. MASTENBROOK.
